CIGARETTE HOLDER

William R. Dickins, Sr., Enterprise, Fla.

Application November 28, 1951, Serial No. 17,548

Term of patent 14 years

(Cl. D85—8)

To all whom it may concern:

Be it known that I, William R. Dickins, Sr., a citizen of the United States, residing at Enterprise, in the county of Volusia and State of Florida, have invented a new, original, and ornamental Design for a Cigarette Holder, of which the following is a specification, reference being had to the accompanying drawing, forming part thereof.

I claim:

The ornamental design for a cigarette holder, as shown.

WILLIAM R. DICKINS, Sr.
